UNITED STATES PATENT OFFICE.

CHARLES C. ABEL, OF HARRIMAN, TENNESSEE.

BLANK FORM.

1,299,531.

Specification of Letters Patent. Patented Apr. 8, 1919.

Application filed April 14, 1917. Serial No. 162,022.

To all whom it may concern:

Be it known that I, CHARLES C. ABEL, a citizen of the United States, residing at Harriman, in the county of Roane and State 5 of Tennessee, have invented a new and useful Improvement in Blank Forms, of which the following is a specification, reference being had to the accompanying drawing.

My improvement relates to account forms 10 comprising ledger sheets and index sheets, the sheets being put together in loose-leaf binders or arranged loosely in card ledger form.

The objects of the invention are (1) to 15 produce a ledger comprising sheets ruled for a single or full-page account, while other sheets are ruled to receive more than one such account, and (2) to closely associate the account sheets with the index sheets, 20 the full-page account sheets being in one group and the sheets bearing more than one account being in another group.

For convenience in description, the sheets bearing ruling to receive a single account 25 will be termed "full-page account" sheets, while the sheets ruled to receive more than one account are termed "petty account" sheets.

In the accompanying drawings,

30 Figure 1 is a front view of an index sheet, a portion being broken away;

Fig. 2 is a front view of a full-page account, a portion being broken away;

Fig. 3 is a rear view of the same sheet, a 35 portion being broken away;

Fig. 4 is a front view of a petty account sheet;

Fig. 5 is a perspective view of a ledger embodying my improvement.

40 Referring to said drawings, 100 designates the index sheets, 101 designates the full-page account sheets, and 102 designates the petty account sheets.

The full-page account sheet, 101, is of 45 any ordinary ledger form having along its top edge a horizontal head space, 1, and having upright column spaces, 2, 2, extending downward from said head space. Said column spaces may be of any convenient 50 number and grouping.

In said head space is a name space, 3, and an address space, 4, into which are to be written the name and address of the person or firm whose account is to occupy the sheet. 55 At the upper right hand corner is a space, 5, preceded by "Acct. No.". On these full-

page account sheets, this space is to receive numbers assigned to the accounts. In the left hand portion of the head space is a space, 6, preceded by "Sheet No.". This 60 space is to receive a serial number expressing the number of the sheet in the account to which the sheet belongs. All the sheets, 101, are preferably of the same color.

The "petty account" sheet, 102, has rulings for three small ledger accounts, each extending across the width of the page. There are three head spaces, 7, below each of which are ledger column spaces, 8, 8. In each head space is a name space, 9, and an 65 address space, 10, for receiving, respectively, the name and the address of the party whose account is to occupy the space below said head space. In the right hand portion of each head space is a serial designation of 70 the number of the account on the page, said designations being, "Acct. No. 1," "Acct. No. 2," and "Acct. No. 3." In the upper right hand corner of the sheet is a sheet number space, 11, preceded by "Sheet No." 75 All these petty account sheets bear the serial numbers indicating the number of accounts on each sheet; but the sheets of the group are numbered serially; for example, if fifty such sheets are used in a group, they are 80 numbered in the space, 11, from 1 to 50, inclusive, 1 being applied to the first and 50 to the last of said sheets.

These "petty account" sheets are preferably of a color differing from the color of 85 the "full-page account" sheets, 101.

The ruling on the front of the full-page account sheets may be repeated on the back, so that the account for that sheet may extend to both sides. The account forms on 90 the front of the "petty account" sheet may also appear on the back of the sheet, the forms on the two sides of the sheet being together numbered as one series.

The index sheets, 100, are used for index- 95 ing the accounts on the sheets, 101, and 102, one index serving for both classes of accounts.

All the index sheets are alike excepting as 100 to the index characters used to designate the 105 sheets. These index characters may be letters or numbers. The drawings show the letters of the alphabet used serially for designating sheets, and the vowel letters are used for designating divisions of the sheets. 110 For example, the sheet illustrated by Fig. 1 bears in its upper, right hand corner the let-

ter, A, and between the two ends of the sheet are the vowel letters, A, E, and I. On the other side of the sheet are the vowel letters, O, U, and Y. Or this sheet may be followed by another sheet also having A in the upper, right hand corner and having on its front the vowel letters O, U, and Y, substituted for the vowel letters, A, E, I. This sheet, 100, has the head space, 12, and the name 10 column spaces, 13, 13, 13. At the right of each name space is a full-page account number space, 14. At the right of each of said spaces is a petty account space, 15.

In the preferred arrangement, the account 15 sheets which are indexed on any index sheet (or pair of index sheets) are placed directly behind that sheet or pair of sheets, the full-page account sheets being put into one group and the petty account sheets being put into 20 another group. This grouping of the account sheets with each other and with the index sheets reduces labor required for index identification and subsequent location of account sheets. Thus all the accounts in the 25 entire book (or box, if the sheets are used in card form) are grouped in relatively small numbers to which search for a particular account is limited.

In making an entry concerning any account 30 on the index sheets, the appropriate index sheet is found by using the first letter of the name of the account. When the index sheet has been thus found, the name column, 13, is found by taking the first 35 vowel of the name as a guide. When that column has been found, the name is entered in that column, and the class of the account whether "full-page" or "petty," is designated by making an entry in either the 40 column, 14, or the column, 15, at the right of the column in which the name has been entered. If it is a "full-page account," this entry is made in the column, 14; and if it is a "petty account," the entry is made in the 45 column, 15. Thus the entry is given significance through location. The entry further designates the serial position of the sheet to which the entry relates. For example, if the sheet is a "full-page account" 50 sheet and it bears the 17th account of the full-page account class behind that index sheet, the said full-page account sheet is made to bear "17" in the account designation space, 5, of Fig. 2, and the same number 55 —17—is written in said column, 14, opposite said column name. But, if the account sheet is a "petty account" sheet, the serial number (for example, 18) of that sheet in the group of said sheets located behind said index sheet is entered in said number space, 11, of Fig. 4, and said number is entered in the column, 15, at the right of said name on the index sheet. And along 60 with said number may be written a number 65 designating the number which the particu-

lar petty account bears on said sheet. For example, the third account, as shown by Fig. 4, will be designated by associating "3" with said number 18.

This may be done by writing "18" in the left hand portion of the space, 15, and writing "3" in the right hand portion of said space and separating said numbers by an oblique line, a.

I claim as my invention,

1. In an account system, index sheets and account sheets arranged in groups alphabetically, the account sheets being of two kinds, and the index sheets comprising a column of name spaces and two columns of account reference spaces located adjacent and parallel to the column of name spaces and in horizontal alinement, and means for distinguishing the two columns, whereby one is adapted to receive references to accounts of one class and the other to receive references to accounts of the other class, substantially as described.

2. In an account system, index sheets and account sheets arranged in groups alphabetically, the account sheets being of two colors, and the index sheets comprising a column of name spaces and two columns of account reference spaces located adjacent and parallel to the column of name spaces and colored, respectively, to correspond, to the colors of the account sheets, substantially as described.

3. In an account system, index sheets and account sheets arranged in groups alphabetically, the account sheets being of two kinds, and index sheets comprising a column of name spaces and two columns of account reference spaces located adjacent and parallel to the column of name spaces and in horizontal alinement, and means for distinguishing the two columns, whereby one is adapted to receive references to accounts of one class and the other to receive references to accounts of the other class, the account sheets of two kinds which have their accounts entered on the same index sheets being separated into groups and placed beside said index sheets, substantially as described.

4. In an account system, index sheets and accounts sheets arranged in groups alphabetically, the account sheets being of two color classes, and the index sheets comprising a column of name spaces and two columns of account reference spaces located adjacent and parallel to the other column of name spaces and in horizontal alinement, and means for distinguishing the two columns, whereby one is adapted to receive references to accounts of one class and the other to receive references to accounts of the other class, the account sheets having their accounts entered on any one of said account sheets being grouped according to 130

color and said groups placed beside said index sheets, substantially as described.

5. In an account system, index sheets and account sheets arranged in groups alphabetically, the account sheets being of two colors, and the index sheets comprising a column of name spaces and two columns of account reference spaces located adjacent and parallel to the column of name spaces and in horizontal alinement, said reference spaces 10 being colored to correspond to the colors

of the account sheets, the account sheets having their accounts entered on any one of said index sheets being grouped according to color and said groups placed beside 15 said index sheets, substantially as described.

In testimony whereof I have signed my name this 6th day of April, in the year one thousand nine hundred and seventeen.

CHAS. C. ABEL.
